CLAIM

The ornamental design for a housing for an electronic card reader, as shown and described.

DESCRIPTION

FIG. 1 is a front, side, perspective view of a housing for an electronic card reader showing my new design;

FIG. 2 is a rear elevational view thereof;

FIG. 3 is a side elevational view thereof, the opposite side is identical in appearance to that shown; and

FIG. 4 is a front elevational view thereof.

FIG. 1.

FIG. 2.

FIG. 3.

FIG. 4.
